DESIGN FOR A CHRISTMAS DECORATION

Elmer K. Arnold, La Porte, Ind., assignor to The One Gnatt Company, Inc., La Porte, Ind., a corporation of Indiana

Application June 13, 1947, Serial No. 139,674

Term of patent 7 years

(Cl. D29—1)

To all whom it may concern:

Be it known that I, Elmer K. Arnold, a citizen of the United States, and a resident of La Porte, in the county of La Porte and State of Indiana, have invented a new, original, and ornamental Design for a Christmas Decoration, of which the following is a specification, reference being had to the accompanying drawing, forming a part thereof, and in which:

Fig. 1 is a perspective view of a Christmas decoration showing my new design;

Fig. 2 is a top plan view of the same; and

Fig. 3 is a front elevational view of the same.

I claim:

The ornamental design for a Christmas decoration, as shown.

ELMER K. ARNOLD.
